UNITED STATES PATENT OFFICE

2,526,416

WATER-COOLED FURNACE

Gustav A. Rehm, Worcester, Mass., assignor to
Riley Stoker Corporation, Worcester, Mass., a
corporation of Massachusetts

Application August 8, 1947, Serial No. 767,455

10. Claims. (Cl. 122—235)

1

This invention relates to water cooled furnaces, and more particularly to the construction and arrangement of hopper bottom furnaces for the combustion of pulverized coal or similar fuels in suspension.

It has been proposed heretofore to construct the lower portion of a furnace in the form of a V in longitudinal cross section, the front and rear walls of the furnace bottom converging downwardly toward a transverse slot or opening through which the fuel ash is discharged. The side walls of such furnaces are usually provided with upright water wall tubes, but in general it has not been considered feasible to extend these tubes downwardly into the V-shaped portion of the furnace, primarily because of the difficulties involved in supplying water to the tubes. Consequently, the side walls of the hopper bottom have ordinarily been constructed of brickwork without water cooling, and this has resulted in excessive air infiltration and high maintenance expense, besides requiring additional wall supporting means.

It is accordingly one object of the invention to provide a hopper bottom furnace having simple and effective means for water cooling the side walls thereof.

It is a further object of the invention to provide a hopper bottom furnace in which the side walls of the main combustion chamber, as well as the side walls of the hopper bottom, are adequately cooled by water tubes.

It is a further object of the invention to provide, a simple and relatively inexpensive construction for a hopper bottom furnace, in which the side walls are cooled by water tubes and the need for brickwork is avoided.

It is a further object of the invention to provide a hopper bottom furnace having a new and advantageous arrangement of water tubes for cooling the various walls, and a highly effective downcomer system for supplying water to the tubes.

With these and other objects in view, as will be apparent to those skilled in the art, the invention resides in the combination of parts set forth in the specification and covered by the claims appended hereto.

Referring to the drawings illustrating one embodiment of the invention, and in which like reference numerals indicate like parts,

Fig. 1 is a longitudinal sectional view of the lower portion of a water cooled furnace, the section being taken on the line 1—1 of Fig. 2;

Fig. 2 is a section taken on the line 2—2 of Fig. 1;

2

Fig. 3 is a section taken on the line 3—3 of Fig. 1; and

Fig. 4 is a fragmentary plan view taken as indicated by the line 4—4 of Fig. 1.

The embodiment illustrated comprises a furnace or combustion chamber 10 having a front wall 11, a rear wall 12, and two side walls 14, the front wall having an opening 15 therein for the introduction of a suitable fuel, such as pulverized coal, which is burned in suspension. At the rear of the combustion chamber there is mounted a transverse horizontal water drum 16 from which a bank of convection water tubes 18 extends upwardly. An upright baffle 19 is mounted at the front of the tube bank 18 to deflect the furnace gases upwardly in a well-known manner. The usual soot hopper 20 is provided behind the drum 16 to collect particles of soot or ash which may be carried rearwardly over the top of the baffle 19.

The lower portion of the combustion chamber 10 is shaped to provide a hopper bottom which will collect and discharge the ash which is deposited therein from the burning fuel. For this purpose a rear bottom wall 22 slopes downwardly and forwardly from the lower margin of the rear wall 12, and a front bottom wall 23 slopes downwardly and rearwardly from the lower margin of the front wall 11. The lower portions of the sloping walls 22 and 23 are separated by a comparatively narrow transverse slot 24 through which the ashes may drop into an ash pit 26 therebeneath. These sloping walls extend between the side walls 14. An access door opening 27 is provided in one of the side walls, somewhat above the slot 24.

The upper surface of the sloping rear wall 22 of the hopper is protected and cooled by means of a row of inclined water tubes 29 which are connected at their lower ends to a transverse horizontal header 30 located adjacent to the lower edge of the wall. These tubes extend upwardly along the rear wall 12 and the baffle 19. In order that an adequate supply of water may be delivered to the header 30, this header is connected to the water drum 16 by means of a row of downcomer tubes 31 located slightly to the rear of the tubes 29.

The upper surface of the sloping front wall 23 of the hopper is protected and cooled by means of a row of inclined water tubes 33 which are connected at their lower ends to a transverse horizontal header 34 located adjacent the lower edge of the wall. These tubes extend upwardly along the front wall 11. In order that an adequate supply of water may be delivered to the

header 34, its ends are connected to the adjacent ends of the rear header 30 by means of horizontal headers 35. It will be apparent that the headers 30 and 34, in conjunction with the two headers 35, form a header structure of generally rectangular shape which surrounds the ash discharge slot 24.

Provision is made for protecting and cooling the side walls 14. For this purpose a row of spaced water tubes 37 is provided adjacent each side wall. The lower ends of the tubes 37 are connected to the headers 35, and the tubes extend upwardly along the inner surfaces of the side walls 14. These tubes are relatively few in number and comparatively widely spaced, but they are sufficient for the protection of the lower portions of the side walls of the hopper, which are not subjected to very high temperatures in service. Certain of these tubes are bent laterally to avoid interference with the door opening 27. The upper portions of the side walls 14 require additional protection, and accordingly other upright water tubes 38 are arranged to extend along the inner surfaces of these walls. The lower ends of the tubes 38 adjacent each wall are connected to a horizontal header 39 which is located an appreciable distance above the corresponding header 35 but preferably somewhat below the tops of the sloping walls 22 and 23. Each header 39 is positioned at the outer side of the corresponding group of water tubes 37. The tubes 38 are preferably located in a common plane with the tubes 37, except for the end portions of the tubes, which are bent to enter the headers. As best shown in Fig. 1, the tubes 38 adjacent to the central portion of each side wall are widely spaced and alternate with the tubes 37, whereas the tubes 38 adjacent the front and rear portions of the wall are closely spaced. Thus the portion of the wall above the header 39 is protected throughout by closely spaced tubes certain of which extend downwardly to protect the lower portion of the side wall of the hopper.

The headers 39 are adequately supplied with water by an independent downcomer system. For this purpose these headers are extended rearwardly, and a row of tubes 41 connects the drum 16 with the rear portions of the headers. The tubes 41 are located behind the tubes 31, and they are bent laterally (as best shown in Fig. 4) to connect with the headers.

The operation of the invention will now be apparent from the above disclosure. The water tubes 29, 33, 37 and 38 will absorb heat which is radiated from the combustion flame, and some of the water in these tubes will be changed to steam. This will produce an upward flow of the steam and water mixture in these tubes. Water will flow downwardly through the tubes 31 from the drum 16 to the rear header 30, and thence forwardly through the lower side headers 35 to the front header 34. Thus the lower ends of the tubes 29, 33 and 37 will be supplied with water. Water will also flow from the drum 16 downwardly through the tubes 41 to the rear portions of the upper side wall headers 39 and thence forwardly through these headers, thereby supplying water to the lower ends of the tubes 38. Thus an adequate supply of water will be provided for all of the heat exposed tubes, a rapid circulation will be ensured, and there will be no possibility of a reverse flow in any of the tubes.

The construction is comparatively simple and inexpensive. The side walls of the hopper bot-

tom are effectively water cooled, and no brick-work is required in their construction.

Having thus described my invention, what I claim as new and desire to secure by Letters Patent is:

1. A water cooled furnace comprising two opposed upright side walls, two opposed sloping bottom walls extending between the side walls and converging downwardly toward an ash discharge opening, a substantially horizontal lower header located adjacent the lower margin of each side wall, water wall tubes extending upwardly from each of said headers, a substantially horizontal upper header located an appreciable distance above each lower header and at the outer side of the corresponding water wall tubes, other water wall tubes extending upwardly from each of said upper headers, and downcomer means to supply water to all of said headers.

2. A water cooled furnace comprising two opposed upright side walls, two opposed sloping bottom walls extending between the side walls and converging downwardly toward an ash discharge opening, a substantially horizontal lower header located adjacent the lower margin of each side wall, a substantially horizontal upper header located an appreciable distance above each lower header, closely spaced upright water wall tubes associated with the side walls above the upper headers, certain of the said tubes being connected at their lower ends to the upper headers and other of the said tubes extending downwardly past the inner sides of the upper headers to connect at their lower ends with the lower headers, and downcomer means to supply water to all of said headers.

3. A water cooled furnace as covered by claim 2, in which one of the side walls is provided with an access door opening located between the corresponding upper and lower headers, and certain of the downwardly extending tubes are bent laterally to avoid interference with said door opening.

4. A water cooled furnace comprising two opposed upright side walls, two opposed sloping bottom walls extending between the side walls and converging downwardly toward an ash discharge opening, a substantially horizontal lower header located adjacent to the lower margin of each side wall, a substantially horizontal upper header located an appreciable distance above each lower header, upright water wall tubes associated with the side walls above the upper headers and connected at their lower ends to the upper headers, the tubes adjacent to the central portion of each side wall being spaced apart more widely than the tubes adjacent to the front and rear portions of the side walls, other upright water wall tubes located between the said more widely spaced tubes and extending downwardly past the inner sides of the upper headers to connect at their lower ends with the lower headers, and downcomer means to supply water to all of said headers.

5. A water cooled furnace comprising two opposed upright side walls, two opposed sloping bottom walls extending between the side walls and converging downwardly toward an ash discharge opening, a substantially horizontal lower header located adjacent to the lower margin of each side wall, a substantially horizontal upper header located an appreciable distance above each lower header, closely spaced upright water wall tubes associated with the side walls above

the upper headers, alternate tubes adjacent to the central portion of each side wall extending downwardly past the inner sides of the upper headers to connect at their lower ends with the lower headers, the remaining tubes being connected at their lower ends to the upper headers, and downcomer means to supply water to all of said headers.

6. A water cooled furnace comprising two opposed upright side walls, two opposed sloping bottom walls extending between the side walls and converging downwardly toward an ash discharge opening, a substantially horizontal lower header located adjacent to the lower margin of each side wall, a substantially horizontal upper header located an appreciable distance above each lower header, closely spaced upright water wall tubes associated with the side walls above the upper headers, certain of the said tubes being connected at their lower ends to the upper headers and other of the said tubes extending downwardly past the inner sides of the upper headers to connect at their lower ends with the lower headers, a substantially horizontal header located adjacent to the lower margin of each of said sloping walls, water tubes extending upwardly from each of the last-mentioned headers and along the corresponding sloping wall to cool the same, and downcomer means to supply water to all of said headers.

7. A water cooled furnace as covered by claim 6, in which the ends of the said last-mentioned headers are connected to the ends of the lower side wall headers to form a header structure of generally rectangular shape surrounding the ash discharge opening.

8. A water cooled furnace comprising two opposed upright side walls, two opposed sloping bottom walls extending between the side walls and converging downwardly toward an ash discharge opening, a substantially horizontal header associated with each side wall and located an appreciable distance above the ash discharge opening, upright water wall tubes associated with the side walls above the headers, certain of the said tubes being connected at their lower ends to the headers and other of the said tubes extending downwardly past the inner sides of the headers to cool the lower portions of the side walls, downcomer means to supply water to the headers, and other downcomer means to supply water to the lower ends of the said downwardly extending tubes.

9. A water cooled furnace comprising two op-

posed upright side walls, two opposed sloping bottom walls extending between the side walls and converging downwardly toward an ash discharge opening, a substantially horizontal upper header associated with one side wall and located an appreciable distance above the ash discharge opening, upright water wall tubes associated with the said one side wall above the header, certain of the said tubes being connected at their lower ends to the header and other of the said tubes extending downwardly past the inner side of the upper header to cool the portion of the side wall therebeneath, a lower header to which the lower ends of the said downwardly extending tubes are connected, downcomer means to supply water to the upper header, and other downcomer means to supply water to the lower header.

10. A water cooled furnace comprising two opposed upright side walls, two opposed sloping bottom walls extending between the side walls and converging downwardly toward an ash discharge opening, a substantially horizontal upper header associated with each side wall and located an appreciable distance above the ash discharge opening, upright water wall tubes associated with the side walls above the headers, certain of the said tubes being connected at their lower ends to the headers and other of the said tubes extending downwardly past the inner sides of the headers to cool the lower portions of the side walls, inclined water tubes associated with each of the said bottom walls, lower header means adjacent to the ash discharge opening, the lower ends of the said downwardly extending tubes and of the said inclined tubes being connected to the lower header means, downcomer means to supply water to the upper headers, and other downcomer means to supply water to the said lower header means.
